UNITED STATES PATENT OFFICE.

JOHN HENRY RIDINGS, OF COAL CITY, ILLINOIS.

DOOR LOCK.

Application filed March 10, 1923. Serial No. 624,128.

To all whom it may concern:

Be it known that I, JOHN HENRY RIDINGS, a citizen of the United States, residing at Coal City, in the county of Grundy 5 and State of Illinois, have invented certain new and useful Improvements in Door Locks, of which the following is a specification.

This invention relates to improvements in 10 door locks, and more particularly to that class or type in which a latch member is adapted to be locked in its projected or locked position for securely locking the door closed.

15 The improved latch and latch locking mechanism is particularly designed and adapted for use in connection with vehicle doors, such as automobile doors, car doors, and the like. The improved lock resembles 20 the principle of the combination lock in that it requires specific knowledge of the operator or user of the particular manner in which the rotatably mounted two-part key operated tumbler actuating members 25 must be set for locking or unlocking operation by a key from the outer side or by a manually operable member, such as a handle, from the inner side.

30 The primary object of my invention is to provide a generally improved door lock of the type or class indicated which will be exceedingly simple in construction, cheap of manufacture and efficient in use.

35 A further and very important object is the provision of an improved door latch and lock having the advantages of a combination lock and at the same time having the additional advantage of being manipulated from the outer side by a key or manually operated by suitable handles or attachments from the inner side without a key.

40 A further object is the provision of an improved door latch and lock in which the locking mechanism is entirely distinct from 45 and separate of the latching mechanism so that the latter may be readily operated as an ordinary latch when convenient or desirable.

50 There are other features of the invention residing in elemental combinations and particular construction of parts, all as will hereinafter more fully appear.

55 With the above mentioned and other ends in view, the invention consists in the novel construction, arrangement and combination

of parts, hereinafter described, illustrated in one of its embodiments in the accompanying drawings, and particularly pointed out in the appended claims.

Referring to the drawings, forming a 60 part of this specification, Figure 1 is a fragmentary side elevation of an ordinary door and door frame equipped with a lock constructed in accordance with this invention, the latch and latch locking mechanism being 65 in locked position.

Fig. 2, an end view of the same.

Fig. 3, a vertical transverse sectional view 70 of the lock detached from the door, the latch being in elevated or unlocked position and the latch locking and key mechanism being in unlocked position, and the arms of the rotatably mounted key mechanism being out of registration to prevent the operation of the latter, the section being 75 taken substantially on line 3—3 of Fig. 8.

Fig. 4, a similar view of the same with 80 the arms of the rotatably mounted tumbler actuating key mechanism in registration and connected preparatory to the movement 85 of the same in latch locking or unlocking position either by the crank on one side or a key on the other.

Fig. 5, a front elevation of the face side 85 of the same with the latch in closed position, the arms of the rotatably mounted key operated tumbler actuating mechanism being disengaged and out of registration to prevent the operation of the tumblers either by the crank arm on the inner side 90 or the key from the outer side, the dotted lines showing how the "safety" arm may be held in a position for throwing and holding the tumbler actuating mechanism entirely out of commission for the operation 95 of the latching device as an ordinary latch and independently of the locking mechanism.

Fig. 6, an elevation of the reverse or key 100 side of the lock, the latch locking mechanism being in its extreme locked or unlocked position preparatory to the operation of the same by key on one side or a handle on the other.

Fig. 7, a side elevation of the same from 105 the inner or key side thereof, the corresponding plate of the lock casing being removed for the purpose of clearer illustration of the relative position of the parts when in latch locking position.

Fig. 8, a similar view with the latch and latch locking tumbler mechanism in unlocked position.

Fig. 9, a top plan or edge view of the same with the latch and latch locking mechanism in locked position.

Fig. 10, a horizontal cross sectional view, taken on line 10—10 of Fig. 7, the parts being in latch locking position, the arms 10 of the rotatably mounted tumbler actuating and latch locking mechanism being in connected position for locking or unlocking movement either by the crank arms on one side or the key on the other.

Fig. 11, a detailed front elevation of one of the crank or key actuated tumbler plates, detached, and which serves to lock and hold the other tumbler members in their respective latch locking and latch unlocked position.

Fig. 12, an edge view of the same.

Fig. 13, a detailed front elevation of a second tumbler plate disposed in front of the front or lock tumbler, shown in Figs. 11 and 25 12 of the drawings.

Fig. 14, an edge view of the same.

Fig. 15, a top plan or edge view of the third or latch locking tumbler plate for engaging and locking the latch in its door 30 locking or projected position.

Fig. 16, a detailed front elevation of the latch locking tumbler plate shown in Fig. 15.

Fig. 17, a front edge view of the same.

Fig. 18, a detailed front elevation of the fourth or front tumbler plate, removed.

Fig. 19, a front edge view of the same.

Fig. 20, a top plan view of the rotatably mounted two-part key operated tumbler actuating members, detached.

Fig. 21, a top plan view of the latch and latch actuating crank mechanism detached from the lock casing.

Fig. 22, an end view of the two-part tumbler actuating members shown in Fig. 20, detached, the spindle crank and sleeve arm members being in their disconnected or non-registering inoperative position with respect to the actuation of the tumbler plate.

Fig. 23, a detailed front elevation of the first and second tumbler members, detached, and held in their relatively locked position.

Similar numerals of reference designate 55 like parts throughout all the figures of the drawings.

The improved lock is provided with a casing 1, which may be of any suitable and convenient construction, said casing 1, in the 60 present instance, being provided with marginal walls 1^a, the latter being provided with bevelled or dove-tailed lugs 1^b, adapted to enter into and interlock with corresponding notches formed in the marginal edges of the 65 cover or closure plate 1^c. The adjacent cor-

ner portions of the marginal walls 1^a are provided with an off-set recess 1^d, and the cover plate 1^c is provided with an inset portion 1^e, spaced from the off-set recess 1^d and conjointly with the latter forming a latch 70 receiving and containing recess or guide slot, as shown most clearly in Fig. 9 of the drawings.

The cover plate 1^c may be secured by means of screws 1^f, connected to the casing 75 1 and the latter may be secured to the marginal edges of the door 2, by means of screws 3, passing through openings in the lock casing. If desired, however, the casing may be used as a mortise lock by fitting the casing 80 in a similarly shaped mortise recess in the door and in which instance the latch operating spindle and handle and the key operated tumbler actuating spindle and sleeve members may be correspondingly extended. 85

The latch 4, is adapted to be moved into and out of its projected or door locking position in the recess by means of a spindle 5, extending through the lock casing and projecting on opposite sides of the latter a suitable distance to receive and carry suitable operating handles 6, which, in the present instance, are in the specific form of crank members 6 secured, in the present instance, by means of screws 6^a. In the present instance, also, the latch 4 and spindle 5 are provided with a loop 7, affording a projection 7^a, adapted to be engaged by a projection on a latch locking tumbler when it is desired to lock the latch in its closed or locking position, as hereinafter referred to. 95

The latch locking mechanism comprises a plurality of tumbler members adapted to be actuated by means of rotatably mounted relatively movable key operated rotary members, one of said members being provided, in the present instance, with a "safety" member and the other with an operating handle or "false key", said safety and false key members being arranged in 105 cooperative relation to each other to set said parts in one position in a tumbler actuating relation and in another position in a tumbler non-actuating position.

The latch receiving or keeper plate 8, may 110 be of any suitable and convenient construction but, in the present instance, comprises a bracket adapted to be secured by attaching elements or screws 8^a, the main body portion being provided with a vertically extending slot 8^b (see Fig. 2), said slot 8^b being extended for the purpose of adapting the keeper plate to interchangeable use at one side or the other or in the varying positions of the lock and whereby the same 115 may be reversed when desired, the sides of the slot 8^b converging toward the center as at 8^c, so that when the latch is drawn down in cooperative relation to the inclined sides 120 of the door will be securely clamped and held 125 130

in closed position in the door opening or frame as well as preventing any rattling or loosening of the latch, a particularly important feature in the use of the lock as a lock for doors of moving vehicles, such as automobiles or the like.

Referring now to the key operated latch locking tumbler mechanism and viewing and describing the same from the outer or cover 10 plate side thereof, as shown in Figs. 6, 7, 8, 9 and 10 of the drawings, it will be seen that four tumbler plates 9, 10, 11 and 12 are arranged within the lock casing and in the order mentioned, the first plate 9 being 15 mounted adjacent to the closed side of the casing as shown, said first plate 9 being also held against lateral or longitudinal movement, and the second, third and fourth plates, 10, 11 and 12, being held against vertical movement by a guide lug 13, secured to and extending from the closed side of the lock casing. It will be seen also that while the opening 9^a, in the member 9, corresponds in length to the lug 13, it is sufficiently deep 20 to permit the plate 9 to be moved vertically by the key operated rotor 14, which, in the present instance, is mounted on a sleeve 14^a, the latter terminating in a crank or "safety" arm 14^b. The key operated member 14 is provided with a bit or 25 projection 14^c, which when in a predetermined relative position or in registration with the adjacent key operated rotor for co-operating with the other tumbler members, 30 is adapted to initially engage within the large opening 9^b, of the plate 9 and initially elevate the latter a sufficient distance to cause the lug 9^c, to clear the lateral arm 11^a, of the plate 11, so that the bit 15^a, of the second 35 40 key operated head or rotor 15, will be permitted to enter the recess 11^b, of the opening 11^c, of the third or latch locking tumbler member and move the latter to the right so that when the latch is in its projected or 45 closing position, as shown in Fig. 7 of the drawings, the projection 11^d, thereof, will move beneath the projection 7^a of the latch and prevent the latter from being elevated or 50 opened. It will be seen that the rotor head 55 55 60 65 70 75 80 85 90 95 100 105 110 115 120 125 130 135 140 145 150 155 160 165 170 175 180 185 190 195 200 205 210 215 220 225 230 235 240 245 250 255 260 tumblers, one of said rotor members being provided with a safety device and the other with an operating handle whereby to set the parts in tumbler actuating and tumbler non-actuating positions as desired.

2. A door lock, comprising a casing, a rotatably mounted latch and oppositely arranged latch operating handles, key operated tumblers adapted to lock said latch in its projected position, and rotatably mounted crank and key operated members for operating said tumblers, one of said members being provided with a safety member and the other with an operating handle whereby in one position said tumblers will be actuated to lock or unlock said latch and in another position will be prevented from operating said tumblers.

3. A door lock, comprising a casing, a latch provided with a spindle carrying operating handle, key actuated tumblers in said casing adapted to lock said latch in its projected position, and rotatably mounted crank and key operated spindle and sleeve members in said casing for operating said tumblers, one of said members being provided with a safety member and the other with an operating handle in cooperative relation to each other to set said parts in tumbler actuating and tumbler non-actuating positions.

4. A door lock, comprising a casing, a latch having oppositely arranged latch operating handles, key and rotor operated tumblers, one of which is adapted to lock said latch in its projected position, and crank and key operated rotor members for operating said tumblers, one of said rotor members being provided with a safety member and the other with an operating handle whereby in one position said tumblers may be actuated to lock and unlock said latch and in another position will be out of tumbler actuating relation to said tumblers.

5. In a door lock, a casing, a pivoted latch, means for operating said latch, a latch locking tumbler provided with a projection adapted to engage said latch to hold the latter in locked position, a key operated rotor, a plurality of tumblers in cooperative relation to said key operated rotor, and relative movable rotor means whereby in one position said key operated rotor will move said latch locking tumbler into and out of latch locking position and in another position will prevent the operation of said rotor to actuate said tumbler and latch locking members.

6. A door lock, comprising a casing, latch and latch operating mechanism, tumblers and tumbler actuating mechanism one of said tumblers being adapted to engage and lock said latch when the latter is in its closed position, said tumbler mechanism including a key operated rotor member on one side and

a false key operated rotor member on the other, said manually operable false key including a safety device adapted to be moved to a position to prevent the actuation of said tumblers by said rotors either manually or through a key and to be moved to another position to permit the actuation of said tumbler members by said rotors.

7. In a door lock, a casing, a rotatably mounted latch, means for operating said latch, said latch being provided with a projection, a latch locking tumbler provided with a projection adapted to engage said projection of said latch to hold the latter in locked position, a two-part key operated rotor, a plurality of tumblers in cooperative relation to said two-part key operated rotor, and means whereby in one position said key operated rotor will move said latch locking tumbler into and out of latch locking position and in another position will prevent the operation of said rotor to actuate said tumbler and latch locking members.

8. A door lock, comprising a casing, latch and latch operating mechanism, tumblers and tumbler actuating rotor mechanism one of said tumblers being provided with a projection adapted to engage and interlock with said latch when the latter is projected, said tumbler actuating rotor mechanism including a key operated member on one side and a manually operable crank member on the other, said manually operable mechanism including a sleeve carrying a "safety" arm adapted to be moved to a position preventing the actuation of said tumblers and to another position to cause the actuation of said tumbler members either by a key on one side or manually on the other, and means for detachably connecting said "safety" arm to said manually operable crank member.

9. A door lock, comprising a casing, a latch provided with oppositely arranged operating handles, tumblers in said casing, one of said tumblers being provided with a projection adapted to engage and interlock with said latch when the latter is in its projected position, and rotatably mounted relatively movable key operated tumbler actuating rotors, one of said rotors being provided with a sleeve carrying a crank arm for moving the rotors out of registration to prevent the operation of said tumblers and the other with a spindle carrying an operating handle, said crank arm and operating handle serving in one position to permit the simultaneous actuation of such tumblers by the rotary movement of said key operated members and to be moved into non-registering non-operative position relative to said tumbler members.

In testimony whereof I have affixed my signature.

JOHN HENRY RIDINGS.
